Primary Examiner — Michelle E. Wilson*(74) Attorney, Agent, or Firm* — Barlow, Josephs & Holmes, Ltd.**CLAIM**

The ornamental design for a clamping mount for a flashlight, as shown and described.

DESCRIPTION

FIG. 1 is a perspective view of a clamping mount for a flashlight in accordance with the present design;

FIG. 2 is a front view thereof;

FIG. 3 is a rear view thereof;

FIG. 4 is a right view thereof;

FIG. 5 is a top view thereof; and,

FIG. 6 is a bottom view thereof.

The broken lines in the drawings illustrate portions of the clamping mount for a flashlight which form no part of the claimed design.
